ADJUSTABLE POSTER FRAME

Filed Oct. 24, 1927

UNITED STATES PATENT OFFICE

ELMER E. PAINE, OF SANTA ROSA, CALIFORNIA

ADJUSTABLE POSTER FRAME

Application filed October 24, 1927. Serial No. 228,185.

The invention forming part of this application relates to adjustable poster frames.

In the present practice, the poster frame is constructed to fit the poster. The necessity of this arrangement is due to the fact that the posters, which are frequently made of very thin paper, must be supported on a smooth surface, and this surface is usually offered by a billboard.

10 The principal object of the invention is to provide an adjustable poster frame which is adapted to stretch out the posters made of thin paper or the like and to support the same so as to present a smooth surface.

15 Another object of the invention is to provide an adjustable poster frame which is readily adjustable to posters of different sizes and in which beads are provided to reinforce the edges of the poster so as to prevent any undue wear thereof.

20 A still further object of the invention is to provide an adjustable poster frame which is collapsible and is readily portable from one place to the other. Therefore, it is rendered highly desirable for the use of different sizes of posters which must be transferred frequently from one place to the other.

25 Another object of this invention is to provide an adjustable poster frame which is highly useful and simple in construction. Convenience of arrangement, lightness and comparatively low cost of manufacture are further objects which have been borne in mind in the development of the invention.

30 Other objects of the invention, together with the foregoing, will be set forth in the following description of the preferred embodiment of means for practicing the same, which is illustrated in the drawing accompanying and forming part of the specification. It is to be understood that I do not limit myself to the embodiment disclosed in said description and the drawing, as I may adopt variations of my preferred form within the scope of my invention as set forth in the claims.

The invention is clearly illustrated in the accompanying drawing in which—

50 Figure 1 is a side elevation of the poster

frame showing the same set up in a position to support a poster;

Figure 2 is a rear elevation of the poster frame;

Figure 3 is a section taken along the line 55 3—3 of Figure 2;

Figure 4 is a detailed view of the detachable bead for reinforcing the edges of the poster, and

Figure 5 is a sectional view of the frame members taken on the line 5—5 of Figure 3.

The device involves in its general organization a telescoping frame element denoted in its entirety by the numeral 1 and a leg designated by the numeral 2. The poster frame 1 comprises an upper frame member 3 and a lower frame member 4. Each frame member is made of sheet metal bent to an L shape in cross section. A spring clip 5 is formed at one extremity of the frame member, while the other extremity thereof is formed in the shape of an enlarged head 6. The enlarged head 6 on the member 3 extends at an angle to the face thereof on which the clip 5 is formed. The enlarged head on the other member 4 protrudes rearwardly from said member oppositely to the clip 5. The enlarged head is formed preferably by retaining the original width of the member at the end thereof, while the rest of the member is bent to the L cross section. A transverse slot 7 is cut in each head at the unbent edge of the member. A longitudinal slot 8 is disposed substantially at right angles to the slot 7 and at one side thereof adjacent to the bent edge of the member. The frame member 3 has a plurality of indentations 9 thereon.

The indentations form corresponding protrusions on the top of said frame member. As 90 the indentations have approximately the same general dimensions, they readily engage the protrusions on the top of the adjacent frame member, thereby providing a larger frictional surface to sustain the frame members in 95 the relative positions thereof.

Detachable beads are provided for the purpose of reinforcing the edges of the poster in the event of the poster being made from thin paper. Most of the posters are provided with 100

beads at the ends thereof. A poster 10 is shown secured in the frame in Figure 1. Detachable beads, denoted in their entirety by the numeral 11, comprise two bars 12 and 13 pivotally secured to each other at one end thereof, the bar 13 having a bent edge 14 thereon adapted to be pressed against the corresponding straight edge of the bar 12. The edge of the poster 10 is inserted between the bars 12 and 13 and is wrapped around the bar 12. Then the bar 13 is turned around the pivot point so that the bent edge 14 presses the paper against the edge of the bar 12. The detachable beads, with the paper attached thereto, are then pressed into the spring clip 5.

The frame members are so disposed that the spring clips 5 are on the outside ends thereof and the enlarged heads 6 thereon hold the adjacent frame member by means of slots 7. The straight portion of the frame member passes thru the slot 7 in such a manner that the straightening out of the two frame members so as to form an extension of each other presses the frame member against the opposite edges of the slot 7, thereby holding the frame members in place. The friction between the indentations of the upper frame member and the protrusions on the lower frame member are sufficient to prevent any accidental slipping of the frame members relative to each other. The manner in which one of the frame members is engaged by the slot 7 of the enlarged head 6 forming part of the other frame member is clearly shown in the sectional view in Figure 3, which figure also clearly illustrates the cooperation between the indentations of the top frame member and the protrusions of the bottom frame member.

In order to present a straight surface of the poster, after the edges of the poster are secured in the clip 5, the frame members 3 and 4 are pulled apart in the extension of each other, thereby increasing the distance between the spring clips 5 sufficiently to stretch out the poster into a straight and smooth plane.

After the poster frame is firmly secured and stretched in and by the frame 1, the leg 2 is attached thereto. One end of said leg forms a fork 15, one prong of which engages the longitudinal slot 8. The leg 2 is preferably made of two wires welded together and bent at one end thereof to form the fork 15. The other extremity of the leg 2 forms a support by bending the free ends of the wires apart as at 16.

The adjustable poster frame operates as follows: The poster 10 made of paper or the like is stretched out approximately to its full length. Then the detachable beads 11 are attached to the ends thereof, and the beads and the paper are secured into the spring clips 5. The frame members 3 and 4 are then pulled

apart, longitudinally sliding on each other, until the poster 10 is stretched to the desired tension and smoothness. After the poster presents a smooth surface in the frame 1, the fork 15 is placed in a position to engage the longitudinal slot 8 in the loop 6 of the lower frame member 4, and the leg 2 is pivoted rearwardly far enough to support the poster in a desired inclined position.

In manufacturing the device, while the various elements may be constructed in any suitable manner and of any suitable material, yet it is preferable to form the same from sheet metal stamping on account of the cheapness, lightness, and strength of the latter, but irrespective of these details in manufacturing, the essential features of the invention are always preserved.

It will be recognized that a particularly facile device is provided to accomplish the above described method of supporting a poster; and one which combines light weight and sensitivity of adjustment and ready adaptation to different sizes of posters with a ruggedness of construction and positiveness of operation, especially adapting it for its use. Being a unitary character, the device requires no careful setting up and lends itself to effective application by the labor ordinarily available.

Having thus described my invention, what I now claim as novel and desire to secure by Letters Patent is:

1. A poster frame comprising a plurality of telescoping frame members, the free end of each frame member being adapted to receive an edge of a poster, the other end of each member being formed with an enlarged head bent out of the plane of said member and slotted, so as to allow cross-wise insertion and the holding of the other frame member therein; and a leg secured to said frame members.

2. A poster frame comprising a plurality of frame members, means on the outer ends of said frame members for holding the opposite edges of a poster, the inner end of each frame member being bent and slotted so as to hold the other frame member therein in an adjusted position and a leg secured to said frame members.

3. A poster frame comprising a plurality of frame members, an enlarged head on one end of each frame member for slidably holding the adjacent frame member therein, said enlarged head being so bent and slotted as to allow the crosswise insertion of one member into the enlarged head of the other member, means on the free end of each frame member for holding the opposite edges of a poster.

4. A poster frame comprising a plurality of frame members, an end of each frame member being bent and having a transverse slot therein for allowing crosswise insertion of the adjacent frame member thereto, means on the free end of each frame member

for holding the opposite edges of a poster, each frame member having a longitudinal slot therein, and a leg removably secured in one of said longitudinal slots.

5. A poster frame comprising a plurality of frame members, each frame member having a slot in one end thereof for slidably engaging the adjacent frame member, resilient means on the free end of each frame member for holding the opposite edges of a poster, each frame member to have a second slot therein, and a leg removably secured in one of said slots.

6. A poster frame comprising a plurality of frame members, an end of each frame member being bent and having a transverse slot therein for allowing crosswise insertion of the adjacent frame member therein, resilient means on the free end of each frame member for holding the opposite edges of a poster, each frame member having a longitudinal slot therein, a leg removably secured in one of said longitudinal slots, and protrusions on each frame member, said frame members having indentations thereon complementary to said protrusions for resisting the relative sliding of said frame members.

7. A poster frame comprising a plurality of frame members, an enlarged head on one end of each frame member being bent out of the plane of said member and being formed with a transverse slot therein for slidably engaging the adjacent frame member, a spring clip disposed at the free end of each frame member for holding the opposite edges of a poster, and protrusions on each frame member, the convex sides of said protrusions on one frame member engaging the concave sides of the protrusions on the adjacent frame member.

8. A poster frame comprising a plurality of frame members, an enlarged head on one end of each frame member being bent out of the plane of the respective members and being formed with a transverse slot therein for slidably engaging the adjacent frame member, a spring clip disposed at the free end of each frame member for holding the opposite edges of a poster, and protrusions on each frame member, the convex sides of said protrusions on one frame member engaging the concave sides of the protrusions on the adjacent frame member, and a leg removably secured to the enlarged head nearest to the top of the poster frame.

9. A poster frame comprising a plurality of frame members, an enlarged head on one end of each frame member, said enlarged heads being bent in opposite directions to each other, each head having a transverse slot therein so disposed as to allow the crosswise insertion of the adjacent frame member thereinto, a spring clip disposed at the free end of each frame member for holding the opposite edges of a poster, and protrusion on each frame member, the convex sides of said

protrusion on one frame member engaging the concave sides of the protrusions on the adjacent frame member, each of said heads having a longitudinal slot therein, and a leg having a bifurcated end inclosing said frame members and engaging the longitudinal slot in one of said heads.

10. A poster frame comprising a plurality of frame members, a head on one end of each frame member being bent out of the plane of the respective members and being formed with a transverse slot therein for slidably engaging the adjacent frame member, a spring clip disposed at the free end of each frame member for holding the opposite edges of a poster, protrusions on each frame member, the convex sides of said protrusion on one frame member engaging the concave sides of the protrusions on the adjacent frame member, each of said heads having a longitudinal slot therein, a leg having a bifurcated end inclosing said frame members and engaging the longitudinal slot in the head nearest to the top of the frame, and clip beads adapted to detachably reinforce the edges of the poster, said clip beads being held by said resilient frame clips.

11. A poster frame comprising a plurality of frame members, a rearwardly bent head at an end of one of said frame members, and a forwardly bent head at an end of the other frame member, each head having a transverse slot therein, said slots extending from opposite edges of said heads so as to allow the transverse insertion of the respective frame members into the respective slots; and means on the free ends of the frame members for holding the opposite edges of a poster.

12. A poster frame comprising a plurality of frame members, a rearwardly bent head at an end of one of said frame members, and a forwardly bent head at an end of the other frame member, each head having a transverse slot therein, said slots extending from opposite edges of said heads so as to allow the transverse insertion of the respective frame members into the respective slots; protrusions on said frame members, the convex side of the protrusions on one frame member engaging the concave sides of the protrusions on the other frame member for offering frictional resistance against relative movement; and means on the free ends of the frame members for holding the opposite edges of a poster.

13. A poster frame comprising a plurality of frame members, a rearwardly bent head at an end of one of said frame members, and a forwardly bent head at an end of the other frame member, each head having a transverse slot therein, said slots extending from opposite edges of said heads so as to allow the transverse insertion of the respective frame members into the respective slots; said rearwardly bent head extending beyond an edge

of the frame members and having a longitudinal slot on the lower edge thereof; a leg detachably secured in said longitudinal slot for supporting the frame in an upright position; and means on the free ends of the frame members for holding the opposite edges of a poster.

14. A poster frame comprising a plurality of frame members, a rearwardly bent head at an end of one of said frame members, and a 10 forwardly bent head at an end of the other frame member, each head having a transverse slot therein, said slots extending from opposite edges of said heads so as to allow the transverse insertion of the respective 15 frame members into the slots; said rearwardly bent head extending beyond an edge of the frame member and having a longitudinal slot on the lower edge thereof; a leg having a bifurcated end enclosing said frame member, a 20 branch of said bifurcated end being detachably secured into said longitudinal slot.

In testimony whereof I affix my signature.
